(57) **CLAIM**

We claim the ornamental design for a machine housing, as shown and described.

DESCRIPTION

FIG. 1 is an isometric view of an embodiment of our design for a machine housing;

FIG. 2 is a right side view thereof;

FIG. 3 is a left side view thereof;

FIG. 4 is a front view thereof;

FIG. 5 is a top view thereof;

FIG. 6 is a bottom view thereof; and,

FIG. 7 is a rear view thereof.

The broken lines in the drawings depict portions of the machine housing which form no part of the claimed design.
